DESIGN FOR A BADGE

Howard C. Townsend, Lockport, N. Y., assignor
to Firemen's Association of the State of New
York, a corporation of New York

Application March 24, 1938, Serial No. 76,068

Term of patent 14 years

To all whom it may concern:

Be it known that I, Howard C. Townsend, a citizen of the United States, residing at Lockport, in the county of Niagara and State of New York, have invented a new, original, and ornamental Design for Badges, of which the following is a specification, reference being had to the accompanying drawing, forming a part thereof.

In the drawing—

Fig. 1 is a front elevational view of a badge, showing my new design;

Fig. 2 is a side view of the badge shown in Fig. 1, a conventional means being shown for attaching the badge to a garment.

The dominant feature of the design is shown in full lines.

I claim:

The ornamental design for a badge, substantially as shown and described.

HOWARD C. TOWNSEND.
